SHEET WINDING MACHINE

George E. Gibbs, Attleboro, Mass., assignor to
American Reinforced Paper Company, Attle-
boro, Mass., a corporation of Massachusetts

Application May 16, 1931. Serial No. 537,806

10 Claims. (Cl. 242—66)

This invention relates to machines for winding sheet material into rolls of predetermined length.

In winding relatively wide sheet material such as paper into rolls of predetermined length ready for the market it has been proposed heretofore to wind the sheet material onto an arbor to form a roll containing the desired length of material, whereupon the winding operation has been stopped long enough to permit the workmen to sever the roll from the main source of supply, remove the roll from the winding position, and place the leading end of the sheet material around an arbor ready to wind the next roll.

These several operations involved in forming successive rolls are time consuming, and the present invention relates to improvements adapted to decrease the work involved in winding successive rolls and also to increase the output of the winding machine and insure the accurate winding of the desired length of material upon each roll.

One important feature of the present invention resides in mechanism for moving an empty arbor into the winding position to receive the sheet material to be wound thereon.

Another feature of the invention resides in means for holding the empty arbor against the sheet material while it is being moved into the winding position so as to hold the material in a taut or stretched condition after it is cut from the finished roll and is being placed around the empty arbor ready to be wound thereupon.

Another feature of the invention resides in mechanism for supporting a knife guiding bar and operable to place the bar upon the sheet being wound at the point where the sheet is to be severed, and a further feature resides in measuring means adapted to control the bar positioning mechanism so as to automatically position the bar accurately at the point where it is desired to cut the sheet.

A further feature resides in power operated means for raising one of the winding rolls out of the sheet winding position to facilitate the removal of a complete roll from the winding position.

Still a further feature of the invention resides in improvements in the sheet measuring mechanism whereby the measuring means may be easily and quickly adjusted to facilitate the winding of rolls of any desired length.

Other features of the invention and novel combination of parts in addition to the above will be hereinafter described in connection with the accompanying drawings illustrating good practical forms of the invention.

In the drawings:

Fig. 1 is a perspective view of a sheet wind-

ing machine embodying the features of the present invention.

Fig. 2 is a side elevation of the machine of Fig. 1.

Fig. 3 is a face view of a graduated dial and mechanism associated therewith for measuring the length of the sheet wound upon the roll.

Fig. 4 is an edge view of the parts shown in Fig. 3.

Fig. 5 on an enlarged scale is a perspective view of the mechanism of Fig. 1 for delivering a knife guiding bar to the winding position.

Fig. 6 on an enlarged scale is a side view with parts in section of power actuated means for delivering the knife guiding bar to the winding position.

Fig. 7 is a vertical sectional view through clutch controlled mechanism of Fig. 6.

Fig. 8 is a sectional view taken on the line 8—8 of Fig. 7.

Fig. 9 is a vertical sectional view through the winding mechanism of Fig. 1 showing the leading end of the sheet being placed about an arbor.

Fig. 10 is a similar view showing a knife guiding bar being delivered to a completed roll.

Fig. 11 is a similar view showing a hand knife in position to cut the sheet along the knife guiding bar.

Fig. 12 is a view similar to Fig. 9 showing the position of the parts immediately after the sheet of the completed roll has been severed therefrom.

Fig. 13 is a view similar to Fig. 12 the completed roll having been removed, and the empty arbor having been moved to the winding position.

Fig. 14 is a rear view of measuring mechanism for measuring the length of the sheet wound upon the arbor.

Fig. 15 is a side view of the parts shown in Fig. 14.

Fig. 16 is a top plan view of electrical contact parts of the measuring mechanism of Fig. 15.

Fig. 17 is a front view with parts in section of the machine of Fig. 1.

Fig. 18 is a horizontal sectional view taken on the line 18—18 of Fig. 17.

Fig. 19 is a view similar to Fig. 15 showing a modified construction employing change driving gears for the winding mechanism.

Fig. 20 is a rear view of the change gear mechanism of Fig. 19; and

Fig. 21 is a top plan view of the change gear mechanism, the casing being shown in section.

The present invention has been developed for use upon a slitting and winding machine employed to trim the edges of a wide sheet of reinforced paper and to slit the paper longitudinally into strips of the desired width, and the invention has been illustrated in the drawings in connection with a paper slitting and winding ma-

80

105

120

chine operating upon reenforced multiply paper. It is to be understood however, that the features of the present invention are applicable to winding machines broadly with or without the slitting means, and may be used in connection with winding machines of various constructions and employed to wind different materials.

The winding and slitting machine illustrated in the drawings as having the features of the present invention associated therewith is provided with the side frames 10 and 11 secured in spaced relation to each other by the transversely extending braces or beams 12 and the width of the machine is preferably sufficient to wind a relatively wide sheet of material. The material 13 to be slit on the present machine and wound into rolls of a definite predetermined length ready for the market may be supplied from the large roll 14 conveniently wound upon an arbor, or heavy shaft 15, the ends of which are rotatably supported by the uprights 16 positioned at the rear of the winding machine.

The wide sheet material 13 is shown in the drawings as a reenforced sheet such as paper, having the transversely extending, reenforcing fibers projecting from the edges of the sheet 13 as shown in Fig. 1, this being incident to the construction of the multiply reenforced paper. It is desirable to trim the sheet 13 adjacent its side edges so as to provide the sheet of paper with clean, straight edges and give the sheet the desired width. It may also be desirable to slit the sheet 13 longitudinally into two or more narrower strips and then wind these strips into rolls R ready for the market. This is accomplished in the construction shown by leading the sheet 13 from the source of supply 14 over the counter operating roller 17 rotatably mounted at the rear of the machine upon the uprights 18 and 19 extending upwardly from the side frames 10 and 11 respectively. The sheet 13 is then passed downwardly under the equalizing roller 20, the ends of which roller are journaled in sliding blocks or bearings disposed between the compressed springs 21, the arrangement being such that the roller 20 is yieldingly mounted to accommodate the tension of the sheet 13. This sheet is then led upwardly over an idle roller 22, then under the pair of cooperating driving rollers 23 and 24, which rollers are power driven in a manner to be described. It is desirable to hold the sheet 13 firmly against the surface of the rollers 23 and 24 to facilitate the slitting of the paper and its feeding movement by these power driven rollers, and this is conveniently accomplished by providing the intermediate roller 25, carried by the rocking arms 26, adapted to rotatably support the roller 25 in the valley or depression between the rollers 23 and 24.

As the sheet 13 passes around the front power driven roller 24 it is acted upon by the slitters 27, rotatably supported by the levers 28 fulcrumed at 29 and the forward ends of which are depressed by the springs 30, adapted to press the slitters 27 firmly against the sheet passing around the roller 24 and operable to trim the edges of the sheet, as indicated by 31 in Fig. 1, of the drawings and also to slit the sheet 13 into the desired number of strips. The slitted sheet 13 is passed upwardly around the front power driven roller 24 and is wound upon an arbor 32 which rests in the valley between the rollers 23 and 24 and is held in driving engagement therewith by the upper roller 33, supported by the uprights 18 and 19 for vertical sliding movement.

The mechanism so far described is not new with applicant but has been illustrated in the drawings and briefly described to make clear the features of the present invention which will now be described.

It is desirable to wind the sheet 13 into tight rolls R and it is therefore desirable to provide braking means associated with the supply roller 14 to retard its rotation and thereby place tension upon the sheet 13. This serves to wind the sheet tightly about the arbor 32, but when the sheet is cut upon a completed roll slack will occur in the sheet 13, extending from the source of supply 14 about the front driving roller 24, unless means is provided for holding this sheet in a taut stretched condition while a new arbor is being placed in the valley between the rollers 23 and 24 and the sheet is placed about the arbor preparatory to winding a new roll.

Having this in mind one important feature of the present invention resides in novel means for holding the arbor in engagement with a sheet 13 passing around the roller 24 from the time immediately before this sheet is severed from the completed roll 32 until the leading portion of this sheet is placed in winding engagement with the new arbor. This is accomplished in the embodiment of the invention illustrated by providing the arbor 32 at each end with a reduced tip 34, (see Fig. 5) adapted to enter a guiding slot provided at the inner face of each side frame 10 and 11. To accomplish this a tip receiving opening 35 is provided at each side of the machine adapted to receive a tip 34 so that these tips may move downwardly into the arcuate guiding slots 36. The arbor 32 while inactive normally rests upon the fixed supporting brackets 37, as shown in Figs. 9 and 10, and is adapted to be moved upwardly about the roller 24 into the valley between the rollers 23 and 24, its ends being guided during this movement by the tips 34 traveling in the guiding slots 36. The arrangement is such that the arbor 32 while in its inactive position shown in dotted lines in Fig. 9 lies out of engagement with the traveling sheet 13, but as it is moved upwardly by operating means to be described, to the position in which it is shown in Fig. 12 it is brought into engagement with the sheet 13 passing about the driving roller 24. This is important because the engagement of the arbor 24 at this point and during its movement from this point into the valley between the rollers is relied upon to hold the sheet 13 taut during the removal of a completed roll from the winding position and initiating the next winding operation.

Another important feature of the present invention resides in treadle actuated mechanism adapted to move the arbor 32 from its inactive position of Fig. 9 to its sheet holding position of Fig. 12, and later from this position into the winding position of Fig. 13. This desirable manipulation of the arbor 32 is secured in the embodiment of the invention shown by providing near the front of the machine the rocking shaft 38, the opposite ends of which are rotatably supported by the side frames at 39. The shaft 38 is provided adjacent each end with a downwardly extending lever 40 which is rigidly secured to the shaft and to the outer end of each lever 40 is pivotally secured at 41 an arcuate upwardly extending arm 42, the upper end of which is adapted to engage the arbor 32 and move it upwardly along the arcuate path 36 into the winding position.

In the construction shown the means for rocking the shaft 38 sufficiently to elevate the arbor 32 to the position in which it is shown in Fig. 12 comprises the foot actuated treadle 43, which is 5 pivotally secured to the fixed bracket 44 and an intermediate portion of this treadle is connected to the lower end of the downwardly extending chain 45, the upper end of which is connected to a grooved cam or sheave 46, rigidly secured to 10 the shaft 38. The arrangement is such that when the workman steps on the treadle 43 and moves it downwardly sufficiently to be engaged by the pivoted latch 47 it will be held by this latch in its depressed position to thereby maintain the 15 curved arms 42 partly raised so as to support the arbor 32 in the position in which it is shown in Fig. 12.

After the sheet 13 has been cut from the completed roll and the completed roll has been removed from the winding position it is desirable 20 to impart a further rocking movement to the shaft 38 to cause the arms 42 to carry the arbor 32 upwardly about the roller 24 into the winding position.

25 This further rocking movement is imparted to the shaft 38 by providing the second foot operated treadle 48 having connected to an intermediate portion thereof the downwardly extending chain 49, the upper portion of which is connected to the grooved cam or sheave 50. The arrangement is such that when the workman depresses the treadle 48 the arbor 32 will be pushed upwardly by the curved arms 42 in a manner to cause it to roll upon the curved surface of the 30 roller 24 into the winding position and in this manner the weight of the arbor is utilized to hold the sheet 13 in firm contact with the roller 24 to thereby prevent the sheet from slipping about this roller and becoming slack. As soon 35 as the treadle 48 is released by the workman and the latch 47 is kicked back to release the treadle 43 the arbor lifting mechanism just described will return under its own weight to the normal position in which these parts are shown in Fig. 9. 40 The upper end of each curved, arbor lifting arm 42 is preferably guided by providing the same with a T-shaped block adapted to slide in the arcuate guideway 36.

When a roll R is completed it is desirable to cut 45 the sheet 13 delivered thereto at a point some distance above the surface of the rollers 23; 24, so as to leave a sufficient length of the sheet to facilitate the engagement of the same with the new arbor placed in the valley between the rollers, 50 as will be apparent from Figs. 9, 11, and 12.

In order to facilitate the cutting of the outermost coil of the sheet wound upon the completed roll R it is desirable to introduce a knife guiding bar 51 between the roll and the outermost coil 55 wound thereupon, as shown in Fig. 11 so that a hand knife 52 may readily be passed along the bar 51 to sever the sheet at this point, as shown in Fig. 11. The completed roll or rolls R may then be removed from the winding position by 60 workmen grasping the opposite ends of the arbor 32 in their hands and lifting the arbor with the rolls thereupon upwardly out of the valley between the winding rollers 23 and 24. This will cause the end of the sheet 13 to fall backwardly 65 over the rear roller 23, as shown in Fig. 12. The treadle 48 is then depressed to move the empty arbor 32 from the position of Fig. 12 into the 70 position of Fig. 9 whereupon a tucker blade 53 which normally lies upon a supporting shell 54 is 75 engaged by a workman and manipulated as

shown in Fig. 9, to fold the end of the sheet 13 about the arbor 32 and tuck it down around the arbor as clearly shown in this figure, whereupon the upper roller 33 which is held in a raised position out of the way during the removal of a completed roll, is lowered into engagement with the new arbor. The winding of the sheet upon this arbor may then be effected by rotating the rollers 23, 24, and 33.

As above stated the rolls R are wound upon the present machine ready for the market and it is important that these rolls be wound accurately to a predetermined length, say for example, one hundred yards to the roll. It is difficult for a machine attendant to watch the indicating means, to be described, so that he may stop the winding operation at exactly the right position each time the predetermined length of sheet material has been wound upon the arbor. In order to decrease the tendency of error in the length of material wound upon a roll and relieve the machine attendant from the exacting duty of controlling the length of the sheet wound upon each roll, another important feature of the present invention resides in measuring means 80 and means automatically controlled thereby for depositing the knife guiding bar upon the sheet 85 13 at the point where the sheet is to be severed so that the bar resting upon the sheet at this point will be carried upwardly around the completed roll under the outermost coil of the sheet, 90 as will be apparent from Figs. 10 and 11.

In order to carry out this feature of the invention means is provided for normally holding a knife guiding bar 51 in an inactive position ready 100 to be automatically introduced at the proper time between the roll R and the sheet 13 at the winding point, as shown in Fig. 10. The mechanism shown for accomplishing this comprises the bar supporting arms 54 disposed at the opposite sides of the machine and at the central portion thereof, as shown in Fig. 1, and each arm 54 is provided at its rear end with the pivoted finger 55 provided at its end with the bar engaging jaws 56, adapted to yieldingly engage the 105 knife guiding bar 51. The forward end of each arm 54 is connected by a link 57 to the outer end of a fixed downwardly extending arm or projection 58.

The intermediate portion of each arm 54 is 110 pivotally connected at 59 to the outer end of a crank arm 60, rigidly secured to the rocking shaft 61 disposed near the front of the machine and preferably rotatably mounted in a fixed hollow shaft 62 which shaft has extending downwardly 115 therefrom the fixed arms 58.

The arrangement is such that rotation of the shaft 61 through part of a revolution serves to move the bar supporting arms 54 from their normal lowered position of Fig. 9 to the raised position of Fig. 10 to insert the knife guiding bar between the roll R and sheet 13 to cause this bar to be carried upwardly between the roll and outermost coil to the position in which it is shown in Fig. 11. The winding operation is preferably slowed down before the bar 51 is delivered to the winding position and the winding operation is stopped when the bar has been carried upwardly around the roll to substantially the position of Fig. 11 where the sheet can be conveniently cut along the bar.

The desired rocking movement is imparted to the shaft 61 by power actuated mechanism to be described which in turn is controlled by measuring mechanism, to be described, and 120

adapted to cause the bar 51 to be delivered to the winding position as soon as a definite predetermined amount of material has been wound upon the arbor 32.

5 The winding rollers 23, 24, in the construction shown are driven from a motor 63 which is shown in Fig. 17 as disposed at the left hand side of the machine and this motor drives a sprocket chain 64 adapted to rotate the manually controlled 10 clutch 65, adapted to rotate the front roller 24. The rear roller 23 is driven from the front roller 24 and at the same speed by the cooperating gears 66.

It is desirable to drive the upper roller 33 as 15 well as the lower rollers 23 and 24 in order to facilitate the winding operation and it is found that the winding of the material tightly about the arbor is facilitated by rotating the upper roller 33 at a slightly faster surface speed than 20 the lower rollers 23, 24. The upper roller 33 is driven, in the construction shown, from the right hand side of the machine viewing Fig. 1, by providing this end of the front roller 24 with a driving gear 67 adapted to drive the gear 68, the outer 25 face of which is provided with beveled teeth adapted to drive the beveled gear 68^x mounted upon the upwardly extending vertical shaft 69. This shaft is provided with a slotted keyway and serves to drive the upper beveled gear 70 which 30 meshes with and drives the beveled gear 71 rigidly secured to the right hand end of the upper roller 33. The gearing just described is such that the upper roller 33 will be rotated at a slightly higher surface speed than the lower rollers 23, 24, and a 35 friction slip driving connection 72 is preferably provided between the lower beveled gear 68^x and the shaft 69 to relieve the parts just mentioned from excessive driving strain.

The upper roller 33 is journaled at its opposite 40 ends in heads 73 which are slidably connected to the uprights 18 and 19 for vertical sliding movement, as shown in Figs. 1 and 18 and these heads are preferably rigidly connected by the beam or beams 74, the arrangement being such that the roller 33 may gradually be forced upwardly to accommodate the increased size of the roll R and may be moved upwardly out of the way, by means 45 to be described, when a completed roll is to be removed from the winding position. The weight 50 of the sliding heads 73 and parts connected thereto is partially counter-balanced by the cables 75 which extend upwardly over the grooved pulleys 76, 77, and are provided at their opposite 55 ends with the counter-balancing weights 78. The number of these weights may be varied as desired and the lowermost weight is slidably connected with the guideway 79.

Having described the driving mechanism for the winding rollers 23, 24, and 33, the mechanism 60 for rocking the shaft 61 each time a roll has been wound to the desired size will now be described.

In the construction shown the desired rocking movement is imparted to the shaft 61 by the operating link 80, one end of which is pivotally 65 secured to the outer end of a crank arm 81, rigidly secured to the shaft 61. The opposite end of this link is pivotally secured by the bolt 82 to the operating disk 83 at a point offset from the axis of this rotating disk. The arrangement is 70 such that each time the disk 83 is rotated through one complete revolution the desired rocking movement will be imparted to the shaft 61 to elevate the arms 54 to the position in which they are shown in Fig. 10 and then return them 75 to their lowered position of Fig. 9.

The disk 83 is normally held against rotation in a predetermined position by friction locking means comprising a ball 84 acted upon by the compressed spring 85 mounted within the hollow projections 86 extending upwardly from the gear casting 87. This spring pressed ball 84 is adapted to engage a notch 88 formed in the disk 83 to bring this disk to rest in the same position each time it has rotated through a complete revolution and to hold the disk from accidental rotation.

The operating disk 83 is rigidly secured to a central shaft 89 journaled in the bearings 90 shown in Fig. 7. This shaft is adapted to be periodically rotated from the hollow gear 91 supported by the ball bearings 92 for rotation about the central shaft 89.

The gear 91 is shown as driven by the gear 67 rigidly secured to the front roller 24. The mechanism for periodically rotating the central shaft 89 from the gear 91 may constitute clutch mechanism of well known construction and comprises the sleeve or ring 93 having a plurality of slots adapted to receive the small locking rollers 94. These locking rollers normally engage slightly flattened faces formed about the central shaft 89 and are surrounded by a sleeve-like portion 95 of the hub of the driving gear 91. The sleeve or ring 93 has an outwardly extending disk 96 which is provided with the shoulder 97 adapted to be engaged by the latch 98, pivoted at 99 for rocking movement into and out of engagement with the shoulder 97. (See Fig. 6.)

The arrangement is such that as long as the latch 98 is held in the position in which it is shown in Fig. 6 the sleeve 93 is positively locked against 110 rotation and the driving rollers 94 are prevented from imparting the rotating movement of the gear 91 to the central shaft 89. When, however, the latch 98 is moving out of holding engagement with the shoulder 97, by means to be described, the 115 sleeve 93 will be rotated slightly under the action of the compressed spring 99^x, one end of which acts upon the sleeve 93 and the other end against the pin 100 extending outwardly from the central shaft 89. This slight rotation of the sleeve 93 120 causes the rollers 94 to effect a locking engagement between the gear 91 and shaft 89 to rotate the latter through one complete revolution, whereupon the latch 98 which has again returned to its locking position of Fig. 6 will engage the shoulder 97 of the ring 93 to stop its rotation and release the driving connection between the gear 91 and shaft 89. At the same time the ball 84 will snap into the notch 88 to lock the shaft 89 and its disks 83 against further rotation.

The movement of the latch 98 out of engagement with the shoulder 97 to thereby effect the delivering of the knife guiding bar to the winding position is effected when the desired amount of material has been wound upon the arbor 32 as determined by the counting or measuring mechanism which will now be described.

In the construction illustrated in Figs. 1 to 16 inclusive two measuring devices are shown, one for use in winding say, one hundred yards of material upon an arbor, and the other for use in winding a different number of yards upon an arbor, and in the modified construction shown in Figs. 19 and 20, change gears are associated with the measuring mechanism whereby the gears may be 145 readily changed to produce rolls of any desired length.

The two measuring devices shown in the construction of Figs. 1 to 16 inclusive are conveniently mounted on the upper transversely extending 150

beam 101 and are provided with the graduated disks or dials 102 and 103. The disk 102 is provided with a pointer 104 secured to the central operating shaft 105 and is adapted to be moved by this shaft around the face of the disk, while the disk 103 is provided with a similar pointer 106 adapted to be operated by a central shaft 107.

The shafts 105 and 107 are conveniently operated from the counter operating roll 17 which is provided with a gear 108 (see Fig. 2) adapted to drive the counter operating gear 109. This gear is operatively connected by the beveled gears 110 to the upwardly extending shaft 111 at the upper end of which are provided the cooperating bevelled gears 112 adapted to drive the shaft 113. (See Fig. 14.)

The shaft 113 through the cooperating gears 114 drives the shaft 115 journaled within the casing 116. Upon the shaft or shafts 115 are loosely mounted two worms 117 and 118 of different pitch, and a sliding clutch 119 provided between these worms may be shifted in one direction to effect the rotation of one worm from the shaft 115 and in the opposite direction to drive the other worm from the shaft. The clutch 119 may be shifted by manually moving the rod 120 in the direction of its length to effect the rotation of either of the indicating devices from the counter operating roller. The shaft 105 has rigidly secured thereto a worm gear 121 adapted to be driven by the worm 117 and the shaft 107 is similarly driven from the worm 118 by the worm gear 122.

In employing the counting or measuring mechanism just described care should be taken to see that the pointer 104 or 106 being used points to the zero position when the sheet 13 is to be wound upon a new arbor, as shown in Fig. 9. If for any reason the pointer should not stand at the zero position at this time it may be readily shifted to this position by squeezing the portions 123 and 124 thereof between the fingers to compress the spreading spring therebetween and thereby release the friction driving connection between the pointer and the pointer rotating shaft, (see Fig. 3). The pointer just mentioned is secured to a disk 125 journaled upon the driving shaft 105 and this disk also has secured thereto a projecting finger 126 adapted to operate a counter 127 which serves to count the number of rolls R wound. The disk 125 has adjustably secured thereto a switch closing finger 128 adapted to close a circuit each time the pointer is moved through one complete revolution to thereby excite a solenoid 129 adapted to exert a downward pull upon the rod 130, the upper end of which is connected to the latch 98 above mentioned, and in this manner the latch 98 is released from the shoulder 97 each time a roll of the desired size is wound and the knife guiding bar is to be inserted. The electric circuit for exciting the solenoid 129 is closed in the construction shown by causing the switch operating finger 128 to pass between the lever supported rollers 131, 131^x, see Fig. 16. The roller 131 is mounted upon a fixed lever and the roller 131^x is mounted upon a pivoted lever adapted to operate an electric switch in the casing 132 when this lever is actuated by the passage of the finger 128 between the rollers 131, 131^x. The mechanism is such that the finger 128 will move out from between the rollers 131, 131^x before the winding operation is stopped. This will cut off the current to the solenoid 129 and cause the latch 98 to be returned to its active position under the action of the compressed spring upon the rod 130 to

arrest the rotation of the disk 96 as it completes one revolution. Before the electric contact finger reaches the contact elements it preferably actuates means 133 adapted to ring a bell to warn the machine attendant that it is time to actuate the power driving clutch 65 and slow down the winding operation as the roll approaches the desired size.

Should it be desired to wind a roll having a different length from that adapted to be wound by the indicator devices 102 and 103 it may then be desirable to employ the change gear mechanism shown in the modified construction of Figs. 19 to 21 inclusive. In this modified construction the worm wheel 121 is rotatably mounted on the shaft 105 and has a rearwardly extending hollow hub 134. To this rearwardly extending hub is rigidly secured a gear 135 that meshes with and drives a gear 136 which in turn drives the gear 137, these gears being rotatably mounted within the casing 116. The gear 137 is rigidly secured to and rotates a rearwardly extending shaft journaled in a hub or bearing upon the rear wall of the casing 116, and at the outer end of this shaft is rigidly secured the large gear 138. This large gear meshes with and drives the small gear 139 which is journaled upon a stub shaft carried by the outer end of the adjustable bracket 140. The bracket 140 is mounted for rocking movement about the axis of the driving shaft of the large gear 138 and rotatably supports the gear 139 for movement into driving engagement with a gear 141, which is bolted or otherwise removably secured to the shaft 105. It will be seen from the gear construction just described that the pointer operating shaft 105 may be driven at any desired speed relative to the worm gear 121 by varying the size of the change gears forming the driving connection between the worm gear 121 and shaft 105, and as a result the pointer traveling over the face of the dial 102 may be rotated through a complete revolution upon the winding of any desired number of yards of material upon an arbor 32.

As above stated means is provided for moving the upper roller 33 upwardly away from the roll R so that the latter may be readily removed from the winding position and the winding of a new roll initiated, and since the sliding heads and other parts provided to rotatably support the upper roller 33 are relatively heavy it is desirable to provide power operating means for raising this roller. To this end in the construction shown an operating shaft 142 is provided extending transversely of the machine below the winding mechanism, and this shaft is driven from the motor 63 by the chain 143. At the right hand side of the machine viewing Fig. 1 is provided a clutch 144 adapted to drive the sprocket 145 which in turn drives the sprocket chains 146 extending upwardly to the upper sprocket 147 adapted to rotate a transversely extending shaft 148 journaled at the upper end of the uprights 18 and 19. This shaft has rigidly secured thereto the gears 149 adapted to cooperate with the teeth of the racks 150 supported for vertical sliding movement and the lower ends of which racks are secured to the sliding heads 73. The clutch 144 for controlling the elevation of the roller 33 is controlled by the transversely extending rod 151 adapted to be shifted in the direction of its length by the machine attendant when the roller 33 is to be elevated. This roller is preferably held in its elevated position by a dog or other locking means, not shown, which may be manually 150

released when it is desired to lower the roller 33 into its work engaging position.

It will be understood from the foregoing that by employing mechanical means in accordance with the present invention to convey an empty arbor to the winding position and for delivering the knife guiding bar to the winding position the machine attendants are relieved from the more or less dangerous work of delivering the arbor and bar to these positions by hand, and as a result the time required for the workmen to remove a completed roll from the winding position and start the winding of the next roll is reduced. Furthermore by employing means controlled by the counting mechanism for automatically delivering the knife guiding bar to the winding position at the proper time all rolls will be wound accurately to the proper size. After a completed roll has been removed from the winding position the arbor 32 may be removed therefrom by hand and placed upon the supports 37 for use in winding another roll.

What is claimed is:—

1. In a sheet winding machine, in combination, an arbor adapted to have sheet material wound thereupon, a roller around which the sheet material passes and operable to wind the material upon the arbor, means for supporting a second arbor adjacent said roller but out of the winding position, fixed arcuate guides for guiding the arbor over the surface of said roller as it is moved to the winding position, and treadle actuated means for moving said second arbor over said roller in contact with the sheet passing around the roller to hold the sheet taut as the arbor is moved to the winding position.
2. In a sheet winding machine, in combination, an arbor adapted to have sheet material wound thereupon, means for supporting and rotating the arbor to wind sheet material thereupon, a knife guiding bar, arms for supporting said bar in an inoperative position, and actuating means for moving the arms into and out of position to place the bar on the sheet being wound upon the roll to be carried part way around the roll under the outer coil to facilitate severing the sheet along the bar.
3. In a sheet winding machine, in combination, an arbor adapted to have sheet material wound thereupon, cooperating rollers operable to wind the sheet material upon the arbor and positioned to support the roll of material in the valley between the rollers during the winding operation, a bar adapted to be laid across the sheet at the point where the sheet is to be severed, and means for supporting said bar in an inoperative position and for introducing it between the roll and roller to be carried part way around the roll under the outer coil to facilitate severing the sheet along the bar.
4. In a sheet winding machine, in combination, an arbor adapted to have sheet material wound thereupon, means for supporting and rotating the arbor to wind sheet material thereupon, a bar adapted to be laid across the sheet at the point where the sheet is to be severed, measuring means for measuring the length of the sheet being wound on the arbor, and mechanism controlled by the measuring means and operable to lay said bar upon the sheet at the end of a predetermined length of material to facilitate severing the sheet at this point.
5. In a sheet winding machine, in combination,

an arbor adapted to have sheet material wound thereupon, means for supporting and rotating the arbor to wind sheet material thereupon, a bar adapted to be laid across the sheet at the point where the sheet is to be severed, measuring means for measuring the length of the sheet being wound on the arbor, and mechanism controlled by the measuring means and operable when a predetermined length has been wound on the roll to lay the bar between the roll and sheet so as to place it under the outer coil and facilitate severing the sheet along the bar.

6. In a sheet winding machine, in combination, an arbor adapted to have sheet material wound thereupon, a power driven roller adapted to support and rotate the arbor to wind the sheet thereupon, a bar adapted to be laid across the sheet at the point where the sheet is to be severed, measuring means for measuring the length of the sheet being wound on the arbor, and mechanism controlled by said measuring means and operable to lay said bar upon the sheet to be carried part way around the roll under the outermost coil to facilitate severing the sheet along the bar at a point above the axis of the arbor.

7. In a sheet winding machine, in combination, an arbor adapted to have sheet material wound thereupon, a power driven roller adapted to support and rotate the arbor to wind the sheet thereupon, a bar adapted to be laid across the sheet at the point where the sheet is to be severed, and means for supporting the bar adjacent the winding position and operable to lay the bar on the sheet adjacent the winding point to be carried part way around the roll under the outer coil to facilitate severing the sheet along the bar at a point in spaced relation to the winding point.

8. In a sheet winding machine, in combination, an arbor adapted to have sheet material wound thereupon, a power driven roller adapted to support and rotate the arbor to wind the sheet thereupon, a bar adapted to be laid across the sheet at the point where the sheet is to be severed, and power operated means adapted to lay the bar on the sheet adjacent the roll to be wound under the outer coil of the sheet and facilitate severing the sheet along the bar.

9. In a sheet winding machine, in combination, an arbor adapted to have sheet material wound thereupon, a power driven roller adapted to support and rotate the arbor to wind the sheet thereupon, a knife guiding bar, means for measuring the length of sheet wound upon the arbor, and power operated mechanism controlled by the measuring means and operable to place the bar on the sheet at the end of a predetermined length thereof to facilitate severing the sheet along the bar.

10. In a sheet winding machine, in combination, an arbor adapted to have material wound thereupon, a power driven roller for supporting and rotating the arbor to wind the sheet thereupon, a knife guiding bar, measuring means for measuring the length of the sheet wound on the arbor, power means operable to lay the bar on the sheet so that it will be carried part way around the roll under the outer coil to facilitate severing the sheet along the bar, and electrical means controlled by the measuring means for initiating movement of said power means.
